(57) **CLAIM**

The ornamental design for a bottle with cap, as shown and described.

DESCRIPTION

This application relates to the subject matter in co-filed U.S. Design patent applications Ser. Nos. 29/491,585, 29/491,590, and 29/491,591, filed on May 22, 2014, all herein incorporated by reference.

FIG. 1 is an exploded, perspective view taken from the top, front, and right side of the bottle with cap of the present invention.

FIG. 2 is a front elevation view of the bottle with cap of FIG. 1.

FIG. 3 is a rear elevation view of the bottle with cap of FIG. 1. FIG. 4 is a right side elevation view of the bottle with cap of FIG. 1, the opposite side being a mirror image thereof; and, FIG. 5 is a top plan view of the bottle with cap of FIG. 1.

The broken lines on FIGS. 1 and 5 are shown for the purpose of illustrating unclaimed portions of the bottle with cap and form no part of the claimed design. The dot-dash lines shown in FIG. 1 are for the purpose of identifying an exploded view and form no part of the claimed design.
